UNITED STATES PATENT OFFICE.

RUSSELL K. COLLINS, OF FORT WORTH, TEXAS, ASSIGNOR TO COLLINS PROCESS, INC.,
OF WILMINGTON, DELAWARE, A CORPORATION OF DELAWARE.

HEAT-PROTECTING MEANS FOR EXPANSION TANKS OF HYDROCARBON-REFINING APPARATUS.

Application filed March 24, 1926. Serial No. 97,120.

This invention relates to improvements in hydrocarbon refining apparatus.

The primary object of the invention is the provision of improved means for protecting hydrocarbon refining tanks from the deteriorating effects of the heating medium.

A further object of the invention is the provision of protecting means specifically adapted for use in connection with conversion apparatus for the refining of hydrocarbon materials, such as is set forth in my copending application Serial Number 561,925, filed May 18, 1922, and embodying an insulation tray for protecting the bottom head of the expander tank, the same preferably being detachable and located between the fire box and expander tank as to permit flow of the heating medium from the fire box to the expander tank, without obstruction, and so as to permit the thorough heating of the hydrocarbon vapor in the expander tank, to convert the same according to the process set forth in my copending application Serial Number 563,136, filed May 23, 1922.

Other objects and advantages of this invention will be apparent during the course of the following detailed description.

In the accompanying drawing, forming a part of this specification, and wherein similar reference characters designate corresponding parts throughout the several views—

Figure 1 is a fragmentary sectional view taken longitudinally through the expander tank, showing the same mounted upon a fire box, in relation to a converter unit, and with the detachable insulation tray located between the converter unit and the expander tank for protecting the latter from deteriorating effects of heat.

Figures 2 and 3 are cross sectional views taken substantially on their respective lines in Figure 1 of the drawing.

In the drawing, wherein for the purpose of illustration is shown only a preferred embodiment of this invention, the letter A may generally designate a fire box or housing, upon which the expander tank B may be mounted in any approved manner, with the converter unit C located therebelow and above the heating compartment of the fire box, so that products of combustion may

heat the fluids of both the converter C and tank B. The improved protector means D is used in connection with the expander B, below the same, and preferably above the converter unit C, for protecting the bottom wall of the expander from the deteriorating effects of the heating medium.

The fire box housing A may be of any approved character, and preferably includes the compartment 10, in which the heat may be generated, or thru which the heat may be passed for heating the units B and C. In the form of invention shown, the housing A includes the expander tank supporting base 15, which is of frusto-conical formation, and at the upper edge thereof may have an annular supporting flange 16 of any approved character.

The converter unit C is of that type set forth in my copending application Serial Number 561,925, filed May 18, 1922, and has been described in that application. Suffice to say, it is mounted upon a horizontal axis across the base 15, above the heating compartment 10, and certain hydrocarbon products and other fluids are passed longitudinally thru the converter C, from one end to the other, and therein being subject to the heating medium are vaporized, and the vapor therefrom passes upwardly through a vertical conduit 17, which enters the bottom wall 18 of the expander tank B, and in the expander tank compartment 19 directs these vapors into intermingled relation with the hydrocarbon vapors otherwise entering the tank B.

The expander casing or tank B is preferably of the vertical type, including a cylindrical body 25, provided with a preferably flat bottom wall 18, which may be secured to the body 25 in any approved manner. The tank B also includes a top wall or header 27, and the vertical heat conducting flues or tubes 28 are arranged longitudinally between the bottom and top plates 18 and 27, for the conduction of the heating medium from the fire box into the exit trap or compartment 29 at the top of the expander tank. Normally, a vapor enters the tank B through an inlet conduit 30 at the lower part of the tank, and the hydrocarbon vapors thus entering the tank compartment 19 are subject to certain thermic and me-

chanical expansions, as set forth in my process application above referred to, and the vapors pass out thru the top conduit 32, after conversion. Certain perforated baffle plates 33 are also located in the compartment 19 between the bottom and top headers 18 and 27.

In the support of the tank B upon the fire box housing, an annular angle member 35 may be used, bolted as at 36 to the base 15. This construction, however, may be altered, since it is contemplated to mount the expander tank on a fire box made of fire bricks, and the converter unit C may be directly supported by said fire bricks in lieu of providing the metal base 15.

In connection with the mounting of the flues 28, it is to be noted that certain openings 40 may be provided in the bottom plate 18, having annular flue abutting flanges 41 projecting therein, and upon which the lower ends of flues 28 may rest. These annular shoulders 41, as illustrated in Figures 1 and 3 of the drawings, are provided in the passageways 40 between the top and bottom surfaces 42 and 43 respectively of the plate 18, and so that certain short bottom flues 45 may also enter the lower portions of the passageways 40 to be seated in the plate 18.

The protecting means D for the base plate 18 of the expander tank preferably includes an insulation plate or tray 46, which may be of disk shaped formation, and is preferably detachably supported in a plane parallel with the plate 18, below the plate 18, by means of stay bolts 47, of any approved character, which may have a leak proof connection with the bottom plate 18 of the tank B. These stay bolts 47 upon tightening will draw the detachable insulation plate 46 upwardly into abutment at its peripheral edges with the base 15 of the fire box, to provide an insulating compartment 50 between the plate 18 and the insulation plate 46, so that the heating medium cannot play directly upon the plate 18 for destruction of the same. Sockets 49 are provided inwardly of the upper surface 51 of the insulation tray 46, adapted to receive the lower ends of the short flues 48 above mentioned. The pockets 49 are of course provided with annular shoulders 52 upon which the flues 45 are supported. The passageways 55 of the flues 45 are of course communicative with the fire box compartment 10, below the plates 46, and these flue passageways 55 align in communicating relation with the passageways 60 of the vertical expander flues 28, so that the heating medium may pass unobstructed upwardly from the fire box 10, by the converter C, and through the flues 45 and 28 in order to thermally act on the products in the expander B.

From the foregoing description of this invention it is apparent that a novel type of insulation tray has been detachably provided in connection with an expander tank, so as to permit the unobstructed passage of heating medium through flues provided from the fire box to the expander, in order to carry out the objects of the invention set forth in my process application second above referred to.

If desired the tank B may be made with a double bottom with the flues 28 extending below the top plate through the insulating space 50, and thus do away with the short individual flues 45.

Various changes in the shape, size, and arrangement of parts may be made to the form of invention herein shown and described, without departing from the spirit of this invention or the scope of the claims.

I claim:

1. In hydrocarbon refining apparatus a fire box including a heat compartment, an expander tank supported on the fire box including a bottom wall facing the compartment, a removable plate supported in spaced relation between the bottom plate of the expander tank and the heat compartment of the fire box, and flue tubes extending through said space for directing the products of combustion of the heat compartment through the expander tank.

2. In an apparatus of the class described an expander tank including a body construction having top and bottom plates with a compartment therebetween, flues carried between said bottom and top plate and extending through said compartment, said flues opening at their ends through said top and bottom plates, a fire box including a heat compartment, means supporting the tank over said heat compartment with the bottom plate facing in the direction of the heat compartment, and removable heat insulating means between the fire box compartment and the bottom plate for protecting the latter, said means including ways for directing the heat medium of the heat compartment through the flues of said expander.

3. In an apparatus of the class described a fire box including a heat compartment, an expander tank including a bottom plate and providing a compartment through which flues extend from the bottom plate and having inlet openings through said bottom plate, a removable insulating tray, means detachably connecting said tray to the bottom plate in spaced relation therewith above the heat compartment of the fire box, and heat conducting flues extending between the insulating plate and bottom plate of the tank for directing products of combustion from the fire box through the flues of said expander.

4. Apparatus for the treating of hydrocarbon products comprising a vertically dis-

- posed shell having a compartment therein, spaced top and bottom plates for the shell, flues connected at their upper and lower ends in said top and bottom plates each having 5 passageways therethrough opening at their ends exteriorly of their respective plates and exteriorly of the compartment of the shell, means for passing a hydrocarbon vapor into the lower end of the shell compartment and 10 causing it to exit at the upper end of said compartment, heat insulating means for the lower end of said shell, and means extending thru said heat insulating means for causing heat to travel thru said flue passageway.
- 15 5. In hydrocarbon refining apparatus the combination of a furnace, a substantially cylindrical shaped shell having a compartment therein and including top and bottom walls, tubular flues connected in the top and bottom walls and extending thru said shell in spaced relation therein having passageways therethrough opening exteriorly of the ends of the shell, a supporting casing supported on the furnace, spaced insulator walls in 20 said casing providing a dead air space therebetween, means to clamp said shell on said casing, and auxiliary flues carried by said casing having sealed connection with the passageways of the flues of the shell, said auxiliary flues having passageways aligning with their respective flue passageways of the shell for conveying products of combustion
- from the furnace into the respective flue passageways.
6. In hydrocarbon refining apparatus an 35 upright tank including a bottom having tubes extending through the tank opening on said bottom, a skirt connected with the tank extending below said bottom, an insulation plate spaced below said bottom, and 40 flue tubes extending thru said insulation plate and space to said bottom having passageways for directly conveying products of combustion from below the insulation plate into the tube passageways of the tank, said 45 space between the tank and insulation plate being a sealed dead air space.
7. In hydrocarbon refining apparatus a vertically disposed expander tank having a 50 horizontal bottom, said tank having pipes extending therethrough opening on said bottom, the bottom being provided with openings thru which said pipes extend, a skirt connected with the tank extending therebelow, an insulation plate in said skirt in sealed 55 abutment with the inner surfaces of the skirt in spaced relation below the bottom of said tank providing a dead air space between the bottom of the tank and said skirt, and flue tubes extending across said space having 60 passageways opening below the insulation plate and directly into the passageways of the pipes of said tank.

RUSSELL K. COLLINS.
